GARMENT HANGER

Willis F. Thompson, Portland, Maine, and Albert R. Speare, Weston, Mass., assignors to The Alden Speare's Sons Co., Cambridge, Mass., a corporation of Massachusetts

Application November 2, 1942, Serial No. 464,274

5 Claims. (Cl. 223—88)

This application is a continuation in part of our application Serial No. 444,750 filed May 27, 1942.

The invention relates to an improvement in garment hangers, and the essential object of the invention is to provide a garment hanger, including its hook, in which the use of metal is made unnecessary, although the hook may be made of metal if desired; at the same time to provide a garment hanger possessing all necessary attributes of strength, rigidity, finish, and economy of structure.

More specifically the invention centers around those portions of the hanger adjacent its hook, and the manner in which the hook, when in place, is made to unite with these portions.

The invention can best be seen and understood by reference to the drawings in which—

Fig. 1 is a view in perspective of a garment hanger embodying the invention.

Fig. 2 is a longitudinal cross section through the apex of the hanger.

Fig. 3 is a fractional plan of the tongued ends of the bars with which the hook makes engagement when disconnected.

Fig. 4 is a side elevation in enlarged detail of the apex of the hanger with the hook removed.

Fig. 5 is a cross section through the apex of the hanger showing a modified construction.

Fig. 6 is a side elevation in enlarged detail of the apex of the hanger with the hook removed showing a modified construction.

Fig. 7 is a longitudinal cross section through the apex of the hanger showing a modified construction in that the top bars are provided with shortened tongues.

Fig. 8 is like Fig. 7 excepting that only one of the top bars is provided with a tongue.

Fig. 9 is a longitudinal cross section showing a construction in which the aligned slots or openings, through which the hook passes, are formed only in the tongues.

Fig. 10 is a longitudinal cross section showing a construction in which the tongues are eliminated.

Fig. 11 is a longitudinal cross section showing a construction in which there are no tongues, and no slots or openings in the top bars through which the hook passes.

Referring to the drawings: the body of the hanger comprises a bottom cross bar 1, and top bars 2 and 3, respectively. The top bars connect with the ends of the cross bar, with angular extension upwardly and inwardly therefrom, to overlie the cross bar. 4 is the hook by which the body of the hanger is supported.

The bars 1, 2 and 3 of the hanger are made of

strong paper such as kraft paper, or they may be made of cardboard. They present a unitary structure, the bars 2 and 3 being preferably bent up from the ends of the cross bar 1 out of a single piece. In order to have the necessary strength and rigidity the bar each comprise an intermediate section 5, with relatively deep flanges 6 dependent from the sides thereof. In the completed structure all the flanges have downward projection from the intermediate sections to which they are connected. With the flanges having this downward projection, and with the arms 2 and 3 bent from a single unitary sheet, it is necessary that the blank from which the bars are made be specially preformed, as is well known to those skilled in the art.

The hook 4 is preferably made of vulcanized fibre, or fibre board, and is died out from flat, relatively thick stock in order that the hook may have necessary rigidity and strength. The shank 7 of the hook is made relatively wide, and at the bottom the shank is extended by a foot 8. This foot is appreciably longer in its width than the width of the shank 7 of the hook. It has spaced oppositely inclined top edges 9 and 10, respectively. The inclination of these edges is substantially that of the inclination of the bars 2 and 3 in the completed hanger. At the inner ends of the inclined edges 9 and 10, immediately adjacent its foot the shank of the hook is provided with notches 11 and 12 which present edges overlying the top edges 9 and 10, respectively, and separately cooperating with these respective edges to provide separate 2-point bearings, one above and one below. The foot 8 is, also, provided at either end with upstanding fingers 13 and 14, respectively, which rise from the respective inclined edges 9 and 10 at points outwardly removed from the notches 11 and 12.

The intermediate sections 5 of each of the bars 2 and 3, at the free ends of these bars, is extended by tongues; the intermediate section 5 to the bar 2 being extended by a tongue 15 extending from the end 16 of its intermediate section, and the intermediate section 5 to the bar 3 by a tongue 17 extending from the end 18 of its intermediate section. Thus each tongue projects beyond the ends of the side flanges 6 to the bar from which the tongue extends. At the junction between the tongue and the body of the bar the stock is preferably creased in order that the tongue may be angularly bent in relation to the bar body without distortion.

Cut within each of these tongues, with extension into the end of the intermediate section 5

of the top bar immediately adjacent the tongue, is a longitudinal slot or opening 20. Each of these openings 20 lies substantially one-half part within the tongue and one-half part within the adjacent intermediate section 5 of the bar. The length of each of these openings is substantially equal to the full width of the shank 7 of the hook.

Formed in each of the intermediate sections 5 of the respective bars 2 and 3 at a point rearward of and removed from the opening 20 in the end of the bar, in alignment therewith, is a hole 21. Formed, also, in each of the tongues 15 and 17, forward of and removed from the opening 20 in the tongue, in alignment therewith, is a hole 22.

The assembly is as follows:

The free ends of the inclined top bars 2 and 3 are brought together, with the free ends to the flanges 6 on the bar 3 fitting inside the free ends of the flanges 6 on the bar 2, with the tongue 15 on the bar 2 underlapping the end portion to the intermediate section 5 of the bar 2, and with the tongue 17 on the bar 3 overlapping the end portion to the intermediate section 5 of the bar 2. With the parts thus disposed the free ends of the intermediate sections of the respective bars will meet in a finished apex. The end 16 to the intermediate section 5 of the bar 2 will then engage the ends of the flanges 6 of the bar 3 adjacent to and beneath the end 16 of the intermediate section 5 of the bar 2 at the root of the overlapping tongue 17 to the bar 3 adjacent its end 18. (See Fig. 4.) The openings 20 in the respective bars 2 and 3 and their respective tongue extensions 15 and 17 will then occupy aligned positions centrally disposed within the apex. The holes 21 in the intermediate section 5 of the respective bars 2 and 3 will occupy aligned positions with the holes 22 in the tongues on the respective bars. The parts are now in position to receive the hook. The tip of the hook is first passed through the aligned openings 20 and afterwards the shank 7 of the hook passes through these aligned openings. The passage of the shank 7 of the hook through the aligned openings 20 can only be accomplished by a more or less forcible pull, owing to the fact that, while the openings 20, in the flat as cut, are substantially equal in length to the full width of the shank, yet in the assembled hanger, owing to the fact that they are cut in parts then angularly arranged in an apex, the length of the openings 20 will become relatively lessened when measured horizontally. Consequently the draw of the shank of the hook through the openings in the parts thus angularly arranged will necessarily be a forcible draw, but is easily accomplished owing to the slight give in the material due to its nature.

The passage of the shank through the aligned openings 20 will continue until the inclined top edge 9 of the foot of the hook will engage the intermediate section 5 of the bar 2, and the inclined top edge 10 of the foot will engage the tongue 15 to the bar 2, which tongue is then underlapping the intermediate section of the bar 3. When the inclined top edges of the foot are thus in engagement with the ends of the top bars, these bars will have entered the notches 11 and 12 of the foot and be held between the inclined edges 9, 10 of the foot and the overlying edges of the notches 11, 12, which act to hold down the engaging parts. At the same time the fingers 13 and 14 on the foot will have entered and passed through the holes in the respective bars and tongue. The finger 13 on the foot will then pass

through the aligned holes 21 and 22, one in the intermediate section of the bar 2, and the other in the tongue 17 to the bar 3, which tongue is then occupying overlapping relationship to the intermediate section of the bar 2. The finger 14 on the foot will then pass through the aligned holes 21 and 22, one in the bar 3 and the other in the tongue 15 on the bar 2, which tongue is then occupying an inside underlying relationship to the intermediate section of the bar 3. The fingers on the foot will function not only to connect the ends of the bars 2 and 3, but will hold their ends in proper relation to co-ordinate with the notches in the hook whereby not only will the hook be held in place, but the ends of the top bars will be held so as not to become free of the fingers.

If desired the tongued ends of the bars, which are thus assembled to form an apex, may be treated with some well known type of adhesive capable of adhering to itself, but not to a paper or cardboard. In such case the top side of the tongue 15, and the portion of the under surface of the bar 3 which is underlapped by this tongue, will bear such type of adhesive. Likewise the under surface of the tongue 17, and that portion of the top surface of the bar 2 against which this tongue has bearing, will likewise bear a coating of the adhesive, so that when these parts are brought together they will adhere to one another. Such a construction is illustrated in Fig. 5 where 23 represents the adhesive bond between these various parts.

In Fig. 6 the ends to the flanges on the top bars do not overlap, but simply meet. Their overlapping assembly, however, is the more desirable, especially when relatively thin stock is being used, as the overlap adds to the rigidity of the structure.

The tongues on the free ends of the respective top bars may be made short, as shown in Fig. 7. Thus the necessity of forming holes in these tongues, for the fingers on the foot to pass through, is avoided. In such case the fingers, while passing through the holes in the bars, will simply pass by the ends of the tongues.

Providing the foot of the hook with upstanding fingers 13, 14, which pass through holes in the respective bars, enables the assembly to be more or less abbreviated, if such be desired, especially when the fingers are considered in the light of holding the bars together, and enabling proper engagement to be made by the top bars with the notches 11 and 12 in the shank of the hook.

Thus in Fig. 8 the assembly is provided with but one tongue, preferably the tongue 17 on the top bar 3.

In Fig. 9 the ends of the top bars do not meet in an apex, but the tongues 15 and 17 are brought forward to overlap one another, and the aligned openings 20, through which the hook passes, are formed only in the tongues. In such a construction the fingers on the foot of the hook in engagement with the top bars will hold the assembly in proper conjunctive relation to the notches 11 and 12 in the shank of the hook as previously explained.

In Fig. 10 a construction is shown in which the tongues are entirely eliminated. The ends of the top bars meet in an apex, and the opening 20, through which the hook passes, is formed substantially one-half part within the end of each top bar. Here the fingers on the hook act to hold the ends of the top bars, at the ends of the slot 75 opening 20 through which the hook passes, in

proper conjunctive relation to the notches 11 and 12 in the shank of the hook.

In Fig. 11 a construction is shown in which the top bars do not meet in an apex, nor are there any openings in the tongues, or bars, through which the hook extends. Instead the top bars are shortened in an amount substantially equal to the length of the opening previously formed in the ends of the top bars for receiving the hook. Thus as shown in Fig. 10, the ends of the top bars are separated to form a space 20 through which the hook extends, and the ends 16, 18 of the respective top bars fit within the notches 11 and 12 within the hook where they are held by the fingers on the foot of the hook engaging the top bars as aforesaid.

The constructions shown in Figs. 1 to 9, inclusive, where tongues are employed having openings in them through which the shank of the hook passes, are especially desirable when the top bars are made of relatively light stock, the tongues assisting in giving strength and rigidity to the structure. In such case, however, the fingers connecting the top bars take the strain off the ends of the openings in the tongues, which otherwise might tear out owing to the lightness of the stock. The constructions shown in Figs. 10 and 11, inclusive, where the top bars are not extended by tongues which embrace the shank of the hook, may be employed when the top bars are made of relatively heavy stock.

We claim:

1. In a garment hanger the combination comprising a bottom cross bar, separate top bars connecting with the ends of the bottom bar and occupying inclined positions with relation to it, each of said top bars comprising a channelled bar having an intermediate section with flanges dependent from the sides thereof, each of said top bars having a hole formed in its intermediate section rearward of and spaced from the end of the bar, a hook having a shank passed between the ends of the top bars, said hook having parts including a foot, presenting separate bearings overlapping and underlying, respectively, the ends to the intermediate sections of the respective top bars whereby the hook will be held in place, and the top bars in proper conjunctive relation thereto when the top bars are connected and the ends to the intermediate sections thereof held in place to engage said respective bearings, and fingers upstanding from said foot adapted and arranged, respectively, to pass through said holes in the intermediate sections of the respective top bars whereby the top bars will be connected and the ends to the intermediate sections thereof maintained in engagement with said respective bearings.

2. In a garment hanger the combination comprising a bottom cross bar, separate top bars connecting with the ends of the bottom bar and occupying inclined positions with relation to it, each of said top bars comprising a channelled bar having an intermediate section with flanges dependent from the sides thereof, each of said top bars having a hole formed in its intermediate section rearward of and spaced from the end of the bar, a hook having a shank passed between the ends of the top bars, said hook having, also, a foot having top edges against which the respective intermediate sections of the top bars have bearing, said shank of the hook having parts presenting intermediate sections of the respective top bars and co-operating with the bearings presented by

the top edges of the foot to hold the hook in place and the top bars in proper conjunctive relation thereto when the top bars are connected and the ends to the intermediate sections thereof, held in place to engage said respective bearings, and fingers upstanding from said foot adapted and arranged, respectively, to pass through said respective holes in the intermediate sections of the respective top bars whereby the top bars will be connected and the ends to the intermediate section thereof maintained in engagement with said respective bearings.

3. In a garment hanger the combination comprising a bottom cross bar, separate top bars connecting with the ends of the bottom bar and occupying inclined positions with relation to it, each of said top bars comprising a channelled bar having an intermediate section with flanges dependent from the sides thereof, each of said top bars having a hole formed in its intermediate section rearward of and spaced from the end of the bar, a hook having a shank passed between the ends of the top bars, said hook having, also, a foot having top edges against which the intermediate sections of the top bars, respectively, have bearing, said shank of the hook having notches on edges overlying said top bars, the respective ends to the intermediate sections of the top edges of the foot and overlapping edges of said notches forming sets of separate bearings for the ends to the intermediate sections of the respective top bars when said ends are constrained to lie within said respective notches whereby the hook will be held in place and the top bars maintained in proper conjunctive relation thereto, and fingers upstanding from said foot adapted and arranged, respectively, to pass through said holes in the intermediate sections of the respective top bars whereby the top bars will be connected and the ends to their respective intermediate sections constrained to lie within said respective notches.

4. In a garment hanger the combination comprising a bottom cross bar, separate top bars connecting with the ends of the bottom bar and occupying inclined positions with relation to it, each of said top bars comprising a channelled bar with an intermediate section and flanges dependent from the sides thereof, each of said top bars having a hole formed in its intermediate section rearward of and spaced from the end of the bar, the intermediate section of each of said top bars having a tongue extension, the top bars having also openings in alignment with each other when the intermediate sections are in proper conjunctive relation to a hook passed through said aligned opening whereby the shank of the hook will be embraced by said tongue extensions, a hook having a shank passed through said aligned openings between the ends of the intermediate sections of the top bars said hook having, also, parts including a foot presenting separate bearings overlying and underlying, respectively, the respective ends to the intermediate sections of the top bars whereby the top bars will be held in place and the top bars in proper conjunctive relation thereto when the top sections thereof held in place and the top bars in presenting respective bearings, and fingers upstanding said foot adapted and arranged, respectively, to pass through said intermediate sections of the top bars whereby the top bars will be connected and the ends to the intermediate sections thereof held in place to engage said respective bearings, and fingers upstanding from said foot adapted and arranged, respectively, to pass through said intermediate sections of the top bars whereby the top bars will be connected and the ends to the intermediate sections thereof maintained in engagement with said respective bearings.

hanger the combination comprising 93,074
a bottom cross bar, separate top bars connecting with the ends of the bottom bar and occupying inclined position with relation to it, each of said top bars comprising a channelled bar with an intermediate section and flanges dependent from the sides thereof, each of said top bars having a hole formed in its intermediate section rearward of and spaced from the end of the bar, the intermediate section of each of said top bars having a tongue extension with a hole in it, the respective tongue extensions occupying positions in the assembled structure whereby the hole in the tongue extension to the intermediate section of one top bar will be in alignment with the hole in the intermediate section of the other top bar, said top bars having also openings in alignment with each other when the intermediate sections thereof and their tongue extensions are in proper conjunctive relation to a hook passed through 20 said aligned openings whereby the shank of the

openings be embedded in said tongue extensions, sections of the intermediate sections of the parts including a hook having the ends of the top bars whereby the hook will be held in place and the top bars in proper conjunctive relation thereto when the top bars are connected and the ends to the intermediate bearings, and fingers to engage said foot adapted and arranged, upstanding from said foot through said aligned holes respectively, to pass through said aligned holes in the respective intermediate sections of the top bars and their tongue extensions whereby the top bars will be connected and the ends to the intermediate sections thereof maintained in engagement with said respective bearings.

WILLIS F. THOMPSON.
ALBERT R. SPEARE.
